CLAIM

The ornamental design for a roller support for rifle barrels, as shown.

DESCRIPTION

FIG. 1 is a front, top perspective view of a roller support for rifle barrels showing my new design;

FIG. 2 is a front elevational view thereof with the rear view being a mirror image thereof;

FIG. 3 is a side elevational view thereof with the opposite side being a mirror image thereof;

FIG. 4 is a top plan view thereof; and,

FIG. 5 is a bottom plan view thereof.

Fig. 4

Fig. 5
